UNITED STATES PATENT OFFICE

LOUIS W. GREVE, OF CLEVELAND, OHIO, ASSIGNOR TO THE CLEVELAND ROCK DRILL COMPANY, OF CLEVELAND, OHIO

VALVELESS ROCK DRILL

Application filed May 3, 1928. Serial No. 274,825.

The present invention is directed to improvements in valveless rock drills.

The primary object of the invention is to provide a device of this character so constructed that the shock incident to the piston hammer changing its working stroke will be absorbed in order that the drill can be held and operated with comparative comfort by the drill runner.

10 Another object of the invention is to provide a device of this type constructed and arranged in such manner that the rearward movement of the hammer will be cushioned by live pressure fluid during a portion of the 15 rearward stroke thereof.

Another object of the invention is to provide a drill of this kind wherein the piston hammer will deliver a powerful working blow, the construction being extremely simple, efficient in operation, and which can be manufactured at a small cost.

With these and other objects in view, this invention resides in the novel features of construction, formation, combination and arrangement of parts to be hereinafter more fully described, claimed, and illustrated in the accompanying drawing, in which:—

The figure represents a longitudinal sectional view through the device.

30 Referring to the drawing, 1 designates a cylinder in which is formed a piston chamber 2 opening at its rear end into a cushioning chamber 3. The front end of the chamber 2 is closed, in this instance, by the tappet case 35 4, and in which is located the usual tappet 5.

The rear end of the cushioning chamber 3 is closed by a bushing 6 which has formed integral therewith a sleeve 7, said sleeve extending into the chamber 3, said bushing and 40 sleeve constituting a relatively small rear piston chamber 8. The rear end of the piston chamber 8 opens into the rear constant air chamber 9 formed in the back head 10. The rear wall of the chamber 9 is provided with a 45 pocket 10', the purpose of which will be later explained. Pressure fluid is conducted to the chamber 9 through the passage 11, the flow thereof being controlled by a suitable valve structure.

50 The piston hammer 12 includes a large head

13 reciprocable in the large chamber 2 and a small elongated head 14 operable in the chamber 8. These heads are connected by a reduced neck 15, the presence of which produces an annular groove 16.

The cylinder wall has formed therein a longitudinal passage 17, the rear end of which communicates with the forward end of the chamber 3 through a port 18, there being a port 19 placing the chamber 2 in communication with said passage. The port 19 is alternately opened and closed by the head 13 during reciprocation thereof.

The cylinder wall is further provided with a longitudinal passageway 20 which communicates with the front end of the chamber 2 through a port 21, and with the chamber 8 through a port 22, the latter port being alternately opened and closed by the head 14 of the piston hammer.

Extending longitudinally through the bushing 6 and sleeve 7 is a conduit 23, the forward end of which communicates with an annular channel 24 formed in the wall of the piston chamber 8 adjacent its forward end. The rear end of said conduit opens into the chamber 9 and is constantly supplied with pressure fluid therefrom.

The exhaust port 25 is so located that some pressure built up for cushioning the rearward movement of the piston hammer will pass therethrough to atmosphere. However, sufficient pressure will be maintained in the chamber 3 to cushion the rearward movement of the piston hammer due to the fact that as soon as the head 13 uncovers the port 19 pressure fluid will be admitted to said chamber.

As shown in full lines in the drawing, the piston hammer is about to begin its rearward stroke and is in such position that the pressure fluid from the constant air chamber 9 will pass through the port 22, into the passageway 20, port 21 to act upon the front face of the head 13. As the piston hammer moves rearwardly, and the head 13 uncovers the port 19, pressure fluid passes through the passage 17, through the port 18 into the chamber 3 and builds up pressure therein sufficient to cushion and slow up the rearward movement of the piston hammer. In

this manner the sudden shock incident to the change of stroke of the piston hammer from its forward to rearward stroke is absorbed by the cushioning action of the fluid in the 5 chamber 3 before pressure fluid is distributed for driving the piston hammer forwardly on its working stroke.

As the piston hammer continues its rearward movement the annular groove 16 coincides with the channel 24 and the head 14 cuts off the flow of pressure fluid through the 10 port 22 to the passageway 20. When the annular groove coincides with the channel 24 pressure fluid from the constant pressure 15 chamber 9 flows through the conduit 23, into the channel 24, and from thence past the neck 15 to act against the rear face of the head 13, thus driving the piston hammer forwardly with considerable power to strike the tap- 20 pet 5.

The pocket 10' will obviously aid in cushioning the rearward movement of the piston hammer at time when the rear end of the head 14 enters the same.

25. What is claimed is:—

A drill of the class described, comprising a cylinder having passages formed in its wall, said cylinder having a relatively large piston chamber and a cushioning chamber communicating therewith, a bushing providing a small piston chamber fitted in the rear end of the cylinder, one of the passages connecting the large chamber and cushioning chamber, a piston hammer including a large head and a 30 small head operating, respectively, in the large and small chambers, means for conducting pressure fluid to the bushing, the small head controlling the flow of pressure fluid from the bushing through one of the 35 passages to the front and rear faces of the large head, said large head controlling the flow of pressure fluid through the other passage to the cushioning chamber operating on the rear of said head.

40. In testimony whereof I affix my signature.
LOUIS W. GREVE.
